UNITED STATES PATENT OFFICE.

RICHARD MACHENBACH, OF SCHLEBUSCH, NEAR COLOGNE, GERMANY.

SHRAPNEL-GUIDE.

1,101,136.

Specification of Letters Patent. Patented June 23, 1914.

Application filed March 12, 1912. Serial No. 623,351.

To all whom it may concern:

Be it known that I, RICHARD MACHENBACH, a subject of the German Emperor, and resident of Schlebusch, near Cologne-on-the-Rhine, Germany, have invented a certain new and useful Improvement in Shrapnel-Guides, of which the following is a specification.

This invention has for its object to provide a packing for guide-rods for shells to be fired from fire-arms or guns, the caliber of which is less than that of the shell proper. Such shells are provided with guide rods, which are introduced into the barrel of the fire-arm and before firing must be caused to fit tightly within the bore.

Hitherto it has been usual to form a packing either by fixing to the guide rod two elements provided with plane and parallel surfaces between which is placed plastic material, which, as soon as the gases press the two elements against one another, is pressed outwardly against the surfaces of the bores of the fire-arm, or else a conical packing element has been employed which is loosely connected with a correspondingly shaped conical part of the guide rod and is driven into the same on explosion so that this part is also pressed outward against the wall of the barrel. Finally packing means are also known in which a hollow conical body intended as packing is deformed by the direct action of the gases. All these packing means are imperfect on the one hand for the reason that the pressure of the gases, which is necessary for tightness is not constant, even when exactly equal charges are used because it is dependent on the efficiency of packing which the pressure itself must first produce. On the other hand these packing means are imperfect because the extent of separation or deformation of two conical surfaces or of the extrusion of the plastic packing material between two plane surfaces is not strictly invariable as slight variations in the composition of the material or in the coefficients of friction of the contacting surfaces produce substantial differences. In addition, it is very difficult if not quite impossible to adjust the inertia of two bodies propelled simultaneously by the same agency so that a relative movement of the bodies takes place with exactly the desired energy. These inconveniences are avoided according to the present invention which

provides for the employment of a cartridge projectile serving to produce or itself to afford a packing when shot into a socket formed in an extension of the guide rod, the extension consisting of suitable material, 80 this projectile being preferably cylindrical and of somewhat larger diameter than the cylindrical socket. By shooting the projectile into the packing element it is insured that the pressure of the gases and the packing produced thereby will not be dependent on one another, any uncertainty of production and the correct difference of the acceleration is avoided, because the projectile is accelerated by the pressure of the gases before the latter act upon the projectile proper or rather on the guide rod. A certain volume of powder in the cartridge corresponds therefore to an exactly predetermined impact of the projectile. The cylindrical formation of the projectile and of the socket allows any desired variation of the impact of the projectile in excess of the minimum necessary to drive the projectile into the socket without producing by the varying 80 force (as for example in the case of conical surfaces) a variation of the quality of packing and tightness.

Several embodiments of the invention are represented in the accompanying drawings 85 in which—

Figure 1 is an elevation partly in section of a shell or shrapnel having my guide connected thereto. Fig. 2 shows a cartridge in elevation and a longitudinal section of the rear end of a guide rod provided with one form of packing. Figs. 3, 4, and 5, are partial sectional views of guide rods having modified forms of packings, and Fig. 6 is a transverse section through a barrel, the 95 rifling of which is engaged by the packing material.

As shown in Fig. 1, the shell 1, of usual construction is closed by a cover 5, which has a hollow projection 6, designed to embrace 100 the end of a gun barrel.

A guide rod 13, preferably a drawn tube, is screwed into the projection and forms an annular space 12 for the reception of the end of the gun.

The safety device for holding the percussion bolt 8 is of a well known type, and comprises a bolt 14 which projects through the percussion bolt and is normally held in place by a pin 15 which is connected to a lever 17 110

pivoted on the projection 6 and projecting into said annular space. When placing the shell on the gun barrel the lever 17 is operated to withdraw the pin 15 out of the bolt 14 so that the latter may be removed by the action of a spring 16 to permit the operation of the percussion bolt when the shell is fired.

The guide rod 13 is provided at its rear end with an expansible extension 21 of suitable material (for example copper). This extension, which is formed with a cylindrical socket 21^a, is effected in the construction shown in Figs. 2 and 3 by screwing into the guide rod 13 the threaded part of the extension. In the construction shown in Fig. 4 a special stud 22 is employed, which stud is threaded at one end in the guide rod 13 and at the other into the extension 21. Fig. 5 shews an embodiment in which a tube 24 of copper or the like is sleeved onto the reduced end 25 of the guide rod 13 so that it extends a little beyond the rod.

In all the embodiments the cylindrical projectile 23 (Fig. 2) of the cartridge is shot into the socket, the diameter of the projectile 23 being a little larger than the diameter of the socket. The projectile 23 passes on firing into the socket and expands the wall of the same, so that this wall bears against the inner wall of the barrel and in rifled barrels enters the rifling (Fig. 6) whereby a gas tight packing is formed. In addition, the extension 21 is provided with longitudinal or lateral openings 26, 27, respectively which permit escape of the air from the socket on shooting in the projectile.

I claim—

1. A guide of the character described, comprising a rod having a socket on its rear end composed of a deformable material 40 adapted to be expanded by the action of a projectile driven into the socket on the explosion of the cartridge.

2. A guide of the character described, comprising a rod having a cylindrical socket 45 composed of a deformable material adapted to be expanded by the action of a cylindrical projectile of a larger diameter than the socket.

3. A guide of the character described, 50 comprising a rod having a socket on its rear end composed of a deformable material adapted to be expanded by the action of a projectile driven into the socket, said socket having an opening to permit the escape of 55 air when the projectile enters the socket.

4. A guide of the character described, comprising a rod, a copper tube mounted thereon forming a socket adapted to be expanded by the action of a projectile driven 60 into the socket.

5. A guide of the character described, comprising a rod having a reduced end, a copper tube mounted on said end and forming a socket adapted to be expanded by the 65 action of a projectile driven into the socket on the explosion of the cartridge.
